Fig. 1

Fig. 2

Fig. 3

FIG. 1 is a front perspective view of a pair of spectacles showing my new design;

FIG. 2 is a rear perspective view thereof; and

FIG. 3 is a top plan view thereof.

The temples are shown broken away in FIG. 3 for convenience of illustration.

The dominant features of my design for the pair of spectacles disclosed reside in the portions shown in full lines, said portions being characterized by the outer end portions of the frame having the configuration and arrangement as shown.

The drawing is shaded to indicate contrasting colored areas.

I claim:

The ornamental design for a pair of spectacles, shown and described.
